DISHWASHING MACHINE

Harry P. Messlor, Trenton, N. J., assignor to G. S. Blakeslee & Co., Cicero, Ill., a corporation of Illinois

Application December 31, 1928, Serial No. 329,481

17 Claims. (Cl. 141—9)

This invention relates to dish washing machines, and more particularly to closure means therefor.

In dish washing machines in which the dishes and other articles are washed by sprays projected thereagainst in a housing or casing, it is desirable that suitable closure means be provided to prevent spraying or splashing of the washing solution or water out of the casing through the openings provided for insertion and removal of the dishes and other articles. In the smaller type of machine adapted for use in restaurants, hospitals and similar places and intended to be operated by one person, it is desirable that means be provided whereby the closures at both ends of the housing or casing of the machine can be readily opened and closed to give access to, and to close the casing, as required.

Preferably, this means for operating the doors or closure members should serve to effectively hold the doors in open position so as to give ready access to the machine from either end thereof. It is also desirable that the door supporting and operating means be so constructed as to eliminate possibility of leakage of the water or washing solution from the casing about such parts. Further objects and advantages of my invention will appear from the detailed description.

In the drawings:

Fig. 1 is an end view of a washing machine constructed in accordance with my invention showing the door partly closed with the curtain raised.

Fig. 2 is a front view of the machine showing the doors in partly raised or open position.

Fig. 3 is a section taken substantially on line 3—3 of Fig. 4.

Fig. 4 is a fragmentary front view, on an enlarged scale, of the washing machine showing door operating means applied thereto in accordance with my invention, the doors being in partly open position.

Fig. 5 is a fragmentary view looking toward the back wall of the casing illustrating the relative positions of the members of the door operating means when the doors are closed.

Fig. 6 is an end view of the preferred construction of one of the doors embodied in my invention.

I have illustrated my invention as applied to a washing machine comprising a box-like casing 1 suitably reinforced and provided with angle iron corner posts 2. This casing contains suitable tracks 3, which may be formed of angle strips, for supporting baskets or trays containing the dishes and other articles to be washed.

Spray-heads or boxes 4 may be provided within

the casing above and below the tracks 3 for projecting sprays of washing solution or rinsing water against the dishes and other articles. The spray-heads or boxes 4 are suitably connected to a pipe 5 to which the washing solution or rinsing water may be supplied in a suitable manner, as by means of a pump. A suitable valve 6 controlled by a handle 7 is interposed in pipe 5 for controlling the supply of washing solution or rinsing water to this pipe and to the spray-heads or boxes. The lower portion of casing 1, beneath the tracks 3, constitutes a tank and an overflow pipe 8 opens into this tank to take off the surplus water therefrom. The washing machine so far described is, in general, of known construction and operation and need not be further illustrated nor described in detail.

The casing 1 is provided, at each end thereof, with an opening 9. This opening is defined by the corner posts 2, top plate 1a of casing 1 and 20 the upper edge of the end wall 10 of the lower portion of the casing which constitutes the tank 1b. The water from the spray-heads or boxes 4 is projected against the dishes and other articles within the casing under pressure and it is desirable, therefore, that means be provided for preventing spraying or splashing of this water or washing solution outside of the casing. With this object in view I provide suitable doors which, when in closed position, effectively cover the openings 9 while permitting ready insertion of articles into the casing and removal of the washed articles from the casing.

A flanged journal box 11, closed at its outer end, is bolted or otherwise suitably secured to 35 the upper corner portions of the front and back wall of the casing, adjacent corner post 2. These journal boxes receive the rounded ends of rods 12 of square cross section which extend transversely of the casing parallel to and adjacent top plate 1a 40 thereof. The rounded ends of the rods provide gudgeons 13 which extend through the front and back walls of the casing and into the journal boxes 11 in which the rods are rockably mounted. These rods support the doors for 45 swinging movement about axes extending transversely of the casing. Each door comprises an upper member 14 formed of sheet metal, this upper member being relatively rigid, and a lower readily flexible member in the form of a curtain 15. This curtain may be formed of rubber or of suitable fabric, such as canvas, and is preferably detachably secured to the member 14 at the lower edge thereof by means of snap fasteners comprising socket members 16 secured to the curtain 55.

and cooperating studs 17 secured to member 14. The upper door member 14 is turned outwardly at its upper end at right angles to provide a flange 18 which is suitably secured to one face of rod 12. The door structure is thus secured to the supporting rod therefor, at its upper portion, for swinging movement transversely of the casing for opening and closing the door. When the door is in closed position, the curtain 15 depends from member 14 and extends therefrom to the upper face of an end shelf 19 suitably secured to the outer face of the end walls 10 of the tank 1b, as indicated by dotted lines in Fig. 1.

The curtain 15 is of suitable height to permit ready passage beneath the same, or, more correctly stated, beneath the member 14 of the door, of the baskets or trays containing the dishes and other articles to be washed.

An arm 20 is suitably secured to each rod 12 adjacent front plate or wall 21 of casing 1. This arm is pivotally secured at its outer end, at 22, to the outer end of a link 23, the inner end of which is secured by pin and slot connections 24, to an arm 25 extending radially from a head 26 secured upon the inner end of a stub shaft 27. The two arms 25 are disposed in opposite relation and are aligned diametrically of head 26. By turning the stub shaft 27 in proper direction the doors at the ends of the casing are operated simultaneously and similarly for covering and uncovering the openings 9.

Stub shaft 27 is rockably mounted in a flanged bearing sleeve 29 secured to front wall 21 of the casing, at the outer face thereof, in a suitable manner as by bolt and nut means. A packing nut 30 screws upon the outer end of sleeve 29 and serves to compress a packing member about the stub shaft 27 in a known manner so as to form a water-tight closure about the shaft in a manner well understood in the art. An operating handle or lever 31 is secured upon the outer end of stub shaft 27 in a suitable manner for turning the same. When the lever 31 is turned into substantially horizontal position as indicated in Fig. 5, the links 23 are moved inwardly of the casing and serve to move the doors into closed position.

Inward movement of the doors beyond this position is prevented by angle stop strips 32 secured to the inner faces of the front and back walls of the casing, these strips projecting inwardly of the casing a short distance beyond the corner posts 2, as shown in Fig. 1. To close the doors the lever 31 is moved in a clockwise direction as indicated in Fig. 4.

The doors, when closed, are held in this position by their own weight due to the leverage effect exerted thereby on the rods 12. To open the doors the lever 31 is moved in a counter-clockwise direction, thus swinging the doors upwardly and outwardly into substantial parallelism with the top plate 1a of casing 1. When the doors are in full open position the arms 25 are in substantially horizontal position. The pin and slot connections between the arms 25 and the links 23 permit continued movement of these arms into substantially horizontal position so as to bring the points of connection between the links and the arms approximately on dead center and at opposite sides of the stub shaft 27. The lever 31 is so disposed upon stub shaft 27 as to be, at this time, in vertical position and acts, by its weight, to hold the stub shaft against reverse turning movement. Under such conditions the doors are effectively locked in open position and accidental closing thereof is prevented. This is

advantageous in permitting ready access to the interior of the machine when desired or necessary. It is to be particularly noted that both of the doors are operated by the single lever 31, the operation of these doors being similar and simultaneous. This is advantageous, particularly when the machine is being used by one operator only.

By a single operation of the lever 31 substantially the full area of each end of the casing is 10 uncovered, thus permitting ready access to the interior of the casing and also admitting ample light to the casing from both ends thereof. During washing of articles in the machine both of the doors are in lowered or closed position and 15 the trays or baskets containing the articles are slid into the casing upon the tracks 3, the articles passing beneath the upper door sections or members 14. During insertion of the articles the curtain 15 is momentarily raised but immediately 20 drops back into operative position by its own weight. After the articles have been washed and rinsed they may be removed from the casing at the other end thereof or, if desired, from the same end from which such articles were inserted into 25 the casing. The casing may be of suitable length to receive two or more containers or trays. When there are several trays of articles in the casing to be removed, this can be readily accomplished by turning the lever 31 in proper direction to open 30 the door and the trays of the washed articles can then be removed with facility from either end of the casing. This is particularly advantageous in small machines intended to be operated by one person.

While I have illustrated and described a specific form of my invention I do not desire to be limited to such form since various changes can be resorted to in the construction and arrangement of parts thereof without departing from the spirit 40 and scope of my invention.

In its broader aspects, my invention is intended to cover any suitable means whereby doors or closure members applied to washing machines and similar apparatuses used for washing dishes, metal 45 parts, or other articles, are conveniently opened and closed in such manner as to facilitate operation thereof and access to the interior of the casing or housing of the machine.

What I claim is:

1. In a washing machine, a casing having end openings for insertion and removal of articles to be washed, doors for said openings, a door operating lever for closing and opening the doors, a pair of oppositely related arms secured to the lever, 55 links connected at their outer ends to the doors, and lost motion connections between the inner ends of the links and the respective arms, the connections between the links and said arms being disposed substantially on dead center between the 60 fulcrum of the lever and the connections of the links with the doors when the doors are in full open position.

2. In a washing machine, a casing having end openings for insertion and removal of articles to 65 be washed, rotatable door rods extending transversely of the casing adjacent said openings, doors carried by the rods and rotatable therewith, arms secured to the rods adjacent one wall of the casing, a stub-shaft rockably mounted through 70 said wall, an operating lever secured on the outer end of the shaft, oppositely disposed arms secured on the inner end of the shaft, and links connecting the shaft arms to the respective arms of the door rods for simultaneously opening and 75

closing the doors in accordance with operation of the lever.

3. In a washing machine, a casing having end openings for insertion and removal of articles to be washed, rotatable door rods extending transversely of the casing adjacent said openings, doors carried by the rods and rotatable therewith, arms secured to the rods adjacent one wall of the casing, a stub-shaft rockably mounted through said wall, an operating lever secured on the outer end of the shaft, oppositely disposed arms secured on the inner end of the shaft, and links connecting the shaft arms to the respective arms of the door rods for simultaneously opening and closing the doors in accordance with operation of the lever, the inner ends of the links being on substantially dead center between the shaft and the connections of the links with said door rod arms, when the doors are open.
- 20 4. In a washing machine, a casing having end openings for insertion and removal of articles to be washed, rotatable door rods extending transversely of the casing adjacent said openings, doors carried by the rods and rotatable therewith, arms secured to the rods adjacent one wall of the casing, a stub shaft rockably mounted through said wall, an operating lever secured on the outer end of the shaft, oppositely disposed arms secured on the inner end of the shaft, and links pivoted at their outer ends to the arms of the respective door rods and having their inner ends connected to the shaft arms by pin and slot connections, the inner ends of the links being substantially on dead center between the shaft and the connections of the links with said door rod arms, when the doors are open.

5. In a washing machine, a casing having end openings for insertion and removal of articles to be washed, doors for said openings, a rockably mounted operating shaft, oppositely disposed arms secured to the shaft, operating connections between the arms and the doors, said connections comprising links having their inner ends connected to the respective arms, and an operating lever secured to the shaft, said lever being disposed vertically and depending from the shaft and the inner ends of the links being substantially on dead center, between the shaft and the connections of the links with the doors, when the doors are open.

6. In a washing machine, a casing having end openings for insertion and removal of articles to be washed, journal boxes secured to the front and back walls of the casing and closed at their outer ends, door rods extending transversely of the casing adjacent the top of the respective openings and rockably mounted in said boxes, doors secured to said rods, arms secured to the rods adjacent the front wall of the casing, a bearing sleeve secured to the front wall of the casing, a stub shaft rockably mounted through the sleeve and projecting into the casing, a pair of oppositely disposed arms secured on the inner end of the shaft, links connecting the shaft arms to the arms of the rods, an operating lever secured on the outer end of the shaft, and means forming a water tight closure about said shaft.

7. In a washing machine, a casing having end openings for insertion and removal of articles to be washed, doors for said openings, a bearing sleeve secured to the front wall of the casing, a stub shaft rockably mounted in the sleeve, said sleeve having means associated therewith for forming a water tight closure about the shaft, operating connections between the stub shaft and

the doors, and a door operating lever secured on the outer end of said shaft.

8. In a washing machine, a casing having end openings for insertion and removal of articles to be washed, doors for said openings comprising upper relatively rigid members and lower readily flexible curtain members depending from said upper members, said curtain members being of a height to permit passage of the articles beneath the upper members of the doors when said doors are closed, and means for simultaneously opening or closing said doors.

9. In a washing machine, a casing having end openings for insertion and removal of articles to be washed, doors for said openings comprising upper relatively rigid members and lower readily flexible curtain members depending from said upper members, said curtain members being of a height to permit passage of the articles beneath the upper members of the doors when said doors are closed, said upper members of the doors being mounted at their upper portions for swinging movement on axes extending transversely of the casing, and means for imparting simultaneous and similar swinging movement to the doors for opening and closing them.

10. In a washing machine, a casing having end openings for insertion and removal of articles to be washed, and doors for said openings comprising upper relatively rigid members and lower readily flexible curtain members depending from said upper members, said curtain members being of a height to permit passage of the articles beneath the upper members of the doors when said doors are closed.

11. In a washing machine, a casing having end openings for insertion and removal of articles to be washed, doors for said openings swingable about axes disposed transversely of the casing and adjacent the upper ends of the doors, and mechanism connected with said doors adjacent the upper ends thereof for simultaneously swinging the doors in opposite directions for opening and closing the end openings of said casing, said mechanism including weighted link means associated with said doors tending to open the latter and so angularly arranged that, when the doors are in their closed position, the weight of the doors overcomes the weight of said means, whereby the doors are held closed against the force of said weighted link means tending to open them.

12. In a washing machine, a casing having end openings for insertion and removal of articles to be washed, doors for said openings swingable about axes disposed transversely of the casing and adjacent the top thereof, and means connected with the upper portion of said casing and connected with the upper ends of said doors adjacent the pivotal axes thereof for simultaneously swinging said doors in opposite directions to open and close the end openings of the casing, said means comprising operating mechanism disposed within said casing and an operating member disposed externally of the casing and connected with said operating mechanism to actuate the same.

13. In a washing machine, a casing having end openings for insertion and removal of articles to be washed, oppositely swinging doors for said openings, and means for operating said doors in opposite relation comprising a freely swingable rockable operating member and operating connections between the member and the doors, said connections being disposed at opposite sides of the axis of the rocking movement of and react-

ing against said member and substantially on dead center therewith when said doors are in open position, said member extending downwardly with respect to its axis when said doors are open and being effective by virtue of its downward position for maintaining said dead center relation against the reaction of said connections.

14. In a washing machine, a casing having end openings for insertion and removal of articles to be washed, rotatable door rods extending transversely of the casing adjacent said openings, doors carried by the rods and rotatable therewith, arms secured to the rods adjacent one wall of the casing, a freely swingable member rockably mounted on said wall and carrying substantially oppositely disposed arm portions and a depending handle portion, and links pivoted at their outer ends to the arms of the respective door rods and having their inner ends connected to said oppositely disposed arm portions and reacting against said portions in substantially dead center relationship with respect to the axis of rocking movement of said member, whereby the dependent handle portion is effective to hold the doors open.

15. In a washing machine, a casing having end openings for insertion and removal of articles to be washed, rotatable door rods extending transversely of the casing adjacent said openings, doors carried by the rods and rotatable therewith, arms secured to the rods adjacent one wall of the casing, a freely swingable member rockably mounted on said wall and carrying generally oppositely disposed arm portions and a depending handle portion, and links pivoted at their outer ends to the arms of the respective door rods and having their inner ends pivotally connected to said arm portions, the angular relation between said arm portions and the arms on said rods and the lengths of said links being such that, when the doors are closed, the angle between each of said links and the associated arm portion is approximately a right angle and the angle between each link and the

5 arm on the associated door rod is an obtuse angle, whereby the weight of the doors in closed position is sufficient to hold the handle portion in elevated position, the connections also being such that when the doors are in their open position the arm portions of said freely swingable member and said links are substantially in dead center relationship, whereby the depending handle portion is enabled to exert sufficient force to hold the doors in their open position.

16. In an apparatus having a door, means swingably mounting said door for movement about a generally horizontal axis at the upper portion of the door, and controlling means for the door comprising a freely swingable member 15 mounted for swinging movement about a generally horizontal axis and including an arm portion and a depending weighted portion, and a link pivotally connected with said arm portion and said door, the angular relation between said link 20 and said arm portion being such that when the door is in raised position, said link and said arm portions are in a substantially straight line position, whereby the weight of said depending portion is sufficient to hold the door in its raised 25 position, and when the door is in its closed position the link is disposed substantially at right angles to said arm portion, whereby the weight of the door is sufficient to overcome the tendency 30 of the weighted dependent portion to open the same.

17. Door operating linkage for a door adapted to be raised and lowered, said operating linkage comprising a freely swingable member having an operating arm and a dependent handle portion, 35 and an operating connection between said arm and said door comprising a link having its inner end pivotally connected to said arm, said handle portion being disposed vertically and said link and said arm being substantially in dead center 40 relationship when the door is raised, whereby the weight of said freely swingable depending handle portion is sufficient to hold the door in its raised position.

HARRY F. MESSLOR. 45
